US0D1103909S

(12) **United States Design Patent** (10) **Patent No.:** **US D1,103,909 S**
(45) **Date of Patent:** **** Dec. 2, 2025**

(54) **CHARGING PILE**

(71) Applicants: **Futaijing Precision Electronics (Yantai) Co., Ltd.**, Yantai (CN); **HON HAI PRECISION INDUSTRY CO., LTD.**, New Taipei (TW)

(72) Inventor: **Meng-Hsien Chuang**, New Taipei (TW)

(73) Assignees: **Futaijing Precision Electronics (Yantai) Co., Ltd.**, Yantai (CN); **HON HAI PRECISION INDUSTRY CO., LTD.**, New Taipei (TW)

(**) Term: **15 Years**

(21) Appl. No.: **29/923,447**

(22) Filed: **Dec. 29, 2023**

(30) **Foreign Application Priority Data**

Dec. 15, 2023 (CN) 202330828792.1

(51) **LOC (15) Cl.** **13-02**

(52) **U.S. Cl.**

USPC **D13/107**

(57) **CLAIM**

The ornamental design for a charging pile, as shown and described.

DESCRIPTION

FIG. 1 is a front, bottom, left side perspective view of a charging pile showing my design.

FIG. 2 is a rear, top, right side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines in the drawings illustrate portions of the charging pile that form no part of the claimed design.

1 Claim, 8 Drawing Sheets
